FIG. 2 CRUDE PETROLEUM

UNITED STATES PATENT OFFICE.

CHARLES F. KENNEDY, OF PHILADELPHIA, PENNSYLVANIA, ASSIGNOR TO THE ATLANTIC REFINING COMPANY, OF PHILADELPHIA, PENNSYLVANIA, A CORPORATION OF PENNSYLVANIA.

METHOD OF TREATING OIL.

Application filed May 24, 1919. Serial No. 299,621.

To all whom it may concern:

Be it known that I, CHARLES F. KENNEDY, a citizen of the United States, residing in the city and county of Philadelphia, State of 5 Pennsylvania, have invented certain new and useful Improvements in Methods of Treating Oil, of which the following is a specification.

My invention relates to the treatment of 10 mineral oils, as petroleum, for improving refinery methods and for improving the character and yield of products.

My invention resides in a method of washing mineral oils, as petroleum, including 15 petroleum products, paraffine wax and slack wax, for improving odor or color, or for rendering the same non-emulsifying, by recourse to a suitably diluted solution of soap or soaps, comprising the alkali metal or ammonium salts of those organic or sulfonic 20 acids found in or derived from acid sludge resulting from the treatment by strong or fuming sulphuric acid of petroleum or petroleum distillates or products, and more particularly found in acid coke or tar derived 25 from acid sludge.

My invention resides also in the washing with a suitable solution of soap or soaps comprising alkali metal or ammonium salts 30 of organic acids, including the above mentioned sludge sulfonates, of wax bearing mineral oil, as petroleum, and particularly wax bearing distillate and stock, paraffine distillate, and paraffine slops, prior to chilling and pressing, for improving the crystalline structure of the wax formed upon chilling the oil, with resultant improved pressing qualities of the oil, better and more complete separation of the wax upon the filter 35 medium, a resultant improved slack wax, and a resultant improvement in the filtered or pressed oil.

My invention resides also in washing crude paraffine wax or crude scale wax, produced from ordinary slack wax or slack wax resulting from washing of the wax bearing oil prior to chilling and pressing; and my invention resides further in such method of treating crude paraffine wax or crude scale 45 wax in advance of filtration of the same to effect improved economy and efficiency of the filtering medium, as fuller's earth.

My invention resides also in mixing and then washing, or in washing and then mixing

wax bearing cuts or distillates differing as 55 to their viscosities, whereby the heavier wax bearing cut or distillate may be more directly chilled and pressed without recourse to intermediate cracking distillation; and more particularly, where one of said distillates or 60 cuts, as paraffine slops, is characterized by the amorphous form or extremely fine subdivision of crystals of paraffine wax content therein heretofore preventing satisfactory cold pressing of the same.

My invention resides also in improving the pressing qualities of a wax bearing oil by subjecting it to washing of the character above referred to, whereby a wax bearing oil of viscosity higher, within limits, than 70 has heretofore been found suitable for chilling and pressing, may readily be chilled and pressed because of the formation of the wax upon chilling into larger crystals.

My invention resides in the washing, prior 75 to cold settling, of wax bearing oil, particularly heavy lubricating stock, as cylinder stock, which, upon dilution with naphtha or equivalent, and when chilled, allows more rapid and complete settling therefrom of 80 solids of the nature of petrolatum containing amorphous wax.

My invention resides in the methods hereinafter described and claimed.

For an understanding of some of the 85 numerous modes of practicing my invention, reference is to be had to the accompanying drawings, in which:

Fig. 1 is a chart of one of various examples of fractional distillation of petroleum 90 in connection with which my invention may be practiced.

Fig. 2 is a chart of one of various examples of cracking distillation of petroleum 95 in connection with which my invention may be practiced.

In washing mineral oils, as petroleum or petroleum products, for removing odor, improving color, rendering an oil non-emulsifying, for improving crystalline structure 100 of paraffine wax, etc., with soap solution for removing from the oil or wax solids in finely divided or colloidal state therein, or other foreign matter, as explained and described in the copending application of E. M. Johansen, Ser. No. 295,496, I have discovered it to be a marked and beneficial improvement to employ as the soap or a substantial part

thereof the alkali metal or ammonium salts of organic, as sulfonic acids, found in or derived from acid sludge, and more particularly those found in or derived from acid coke produced from acid sludge, which results from treatment by strong or fuming sulphuric acid of petroleum or petroleum product or distillate. These preferred and more efficient acids and soaps are of the character described in U. S. patent to Taveau No. 1,271,387, and are available in great quantities and of any suitable degree of purity or concentration.

It accordingly will be understood that my invention comprehends the employment of such preferred soaps, sometimes termed "black acid" soaps, for any suitable or desirable washing of an oil, and particularly petroleum or any fraction, cut or product thereof, including gasoline, naphtha, lamp oil, gas oil, etc.

In the hereinafter described methods the washing referred to is also preferably effected by the use of these preferred soaps, though in many of the aspects of my invention it is not limited to the particular character of soap employed.

In Fig. 1 there is indicated in chart form one of various possible modes of procedure for the fractional distillation of crude petroleum, any of the fractions or products of which it will be understood may be washed whenever suitable or desirable, with a solution of my above mentioned preferred soap.

As indicated in Fig. 1, there may be taken separate light and heavy wax bearing cuts or fractions, which may be of any suitable or desired gravities, for example, respectively 37 and 34 degrees Bé. These cuts or fractions may be separately treated as indicated, or they may be mixed or taken as a single fraction or cut and then washed or treated in the manner indicated.

In the example illustrated in Fig. 1, the light wax bearing distillate is washed with a solution of any suitable soap, as alkali metal or ammonium salt of resin acid, fatty acid, naphthenic acid, or sulfonic acid, and preferably my hereinbefore described salt of sulfonic acid derived from or found in acid sludge. The soap is employed in aqueous solution, the quantity of soap and degree of dilution being such as to be insufficient for or prevent emulsification of the oil while undergoing washing, but sufficient or suitable for removing from the oil colloidal solids, finely divided solids in suspension, or other foreign matter. The washing is preferably carried on by agitating the oil and soap solution, as by blowing air therethrough, while at a temperature inducing suitable viscosity of the oil.

The washed wax bearing distillate, which separates from an aqueous layer after the foregoing treatment, has had the conditions

affecting its dissolved paraffine wax content so altered that it forms larger crystals when chilled, as to 32 degrees F. or lower, with the result that when the washed distillate is chilled and pressed, wax more readily and more completely separates therefrom and remains, as usual, upon the filter medium as so-called slack wax, a mixture of paraffine wax and oil. By so washing the wax bearing oil amorphous or very finely divided crystalline wax is in effect converted into wax of large or sometimes long needle-shaped crystals. The slack wax, and in fact the paraffine wax derived from the slack wax, are of markedly improved crystalline structure, and of improved odor and color.

The slack wax resulting from filter pressing the chilled washed wax bearing distillate may be treated in either of two ways as indicated. It may be sweated to procure crude scale wax, which may then be melted and again washed by suitable aqueous soap solution of the character above referred to, but preferably one employing my hereinbefore described soap. The washed crude scale wax may then be melted and filtered, as upon fuller's earth or equivalent, yielding paraffine wax. It will be understood that the washing of the crude scale wax is not essential, and may be resorted to or not, if the light wax bearing distillate was washed. In general, however, and broadly, irrespective of the preceding steps leading to the production of crude scale wax, my invention comprehends washing the same as described, for improvement of its color, and odor, and for improvement of its crystalline structure if the oil in which it was previously contained has not been washed.

Or the slack wax may be melted and washed by any of the suitable soap solutions referred to, and particularly one employing my preferred soap above described. The resulting washed slack wax may then be sweated to produce a crude scale wax, which may then again be similarly washed, when melted, though this washing may readily be omitted if the slack wax is washed. The washed crude scale wax may then be melted and filtered, as upon fuller's earth or equivalent, to produce paraffine wax.

The washing of the wax saves fuller's earth or other filtering material because there is left in the wax less material of character, as coloring matter, removable by filtration.

The yield of slack wax from wax bearing oil washed as herein described is materially greater, in some instances 50% greater than by common methods heretofore employed. Furthermore, the slack wax, or the paraffine wax derived therefrom, contains a relatively large quantity of low melting point wax. For example, where previously paraff-

5 fine wax was ordinarily procured melting at approximately 118 or 132 degrees F., my wax contains not only such high melting point wax, but in addition relatively large quantity or large proportion of lower melting point wax, such, for example, as melts from 105 to 118 degrees F. Because of the washing of the wax bearing oil before chilling and pressing, the fractionation of the 10 wax by sweating is more easily and readily accomplished, and the fractions of different melting points are more sharply defined.

15 The heavy wax bearing stock which may be, for example, of 34 degrees Bé. gravity, may, as heretofore, be subjected to a mild cracking distillation yielding heavy wax bearing distillate. In accordance with my invention this distillate may be washed by suitable aqueous solution of soap, of any 20 of the characters hereinbefore referred to, and particularly my preferred soap as described, the resultant washed distillate being then chilled and pressed, and yielding slack wax. Here again the washing increases the 25 yield and improves the character of the wax remaining upon the filter medium. The slack wax may then be treated by any suitable method, as by either of the methods hereinbefore described in connection with 30 the slack wax resulting from the light wax bearing distillate, to produce paraffine wax or other products.

35 In place of subjecting the heavy wax bearing stock to the above described cracking distillation, it is my preference to avoid such cracking distillation, and this may be accomplished by washing the heavy wax bearing stock by an aqueous soap solution of any of the characters above described. 40 The resultant washed heavy stock is then chilled and pressed, yielding a slack wax which may then be treated by either of the methods above described in connection with slack wax resulting from light wax bearing 45 distillate. In this instance again the washing improves the yield and quality of slack wax remaining upon the filter medium, the washing having effected such conditions 50 as to induce formation of wax of large crystalline structure in lieu of amorphous or finely divided crystalline wax.

55 The paraffine waxes resulting from either of the above described methods of treating heavy wax bearing stock have the desirable characteristics of the hereinbefore described paraffine waxes as to odor, color, and more particularly crystalline structure and melting points.

60 Suitable proportions of the light wax bearing distillate and heavy wax bearing stock may be mixed, for example, in the proportions of 70% of the light wax bearing distillate to 30% of the heavy wax bearing stock, and the mixture washed by suitable 65 aqueous solution of soap as described, and

then chilled and pressed, so yielding a slack wax which may then be treated by any suitable method, as any of the methods above described, for the production of paraffine wax or other products.

70

Or, in place of separating the light wax bearing distillate and heavy wax bearing stock as separate fractions or cuts, they may be taken in combination as a single fraction or cut and then washed in suitable aqueous solution as above described to produce, upon chilling and pressing, a slack wax which may then be treated by any suitable method, as any of the above described methods, to produce paraffine wax or other products.

75

80

In either of the above described cases, where the light wax bearing distillate and heavy wax bearing stock are in mixture, there may be admixed therewith a suitable quantity of low viscosity oil, as gas oil or any other suitable oil, and preferably an oil which has been previously subjected to filter press operation or which may be derived from a pressed distillate. Such admixture of low viscosity oil reduces the viscosity of 85 the mixture for pressing when chilled.

In general, the admixture of such low viscosity oil may be resorted to in connection with any of the oils or mixtures of oils herein described which are to be chilled and 90 pressed, whenever it is found suitable or desirable to lower the viscosity.

95

95 As well understood in the oil refining art, some crude oils are reduced by fractional distillation which drives off only light or 100 low boiling point oils, as naphtha, yielding a so-called reduced oil. This reduced crude oil may then be acid treated, or it may be washed and then acid treated and the resultant sour oil neutralized, or acid treated 105 and then neutralized and washed. In either case the neutralized oil may be fractionally distilled substantially as indicated in Fig. 1, light wax bearing distillate and heavy wax bearing stock resulting, which may be separately treated as indicated in Fig. 1, or which 110 may be treated in mixture as above described.

Furthermore, in fractionally distilling crude petroleum as indicated in Fig. 1, as 11 well as in fractionally distilling the washed or acid treated reduced crude oil last above referred to, there is a residuum in the still which is heavy wax bearing oil, as cylinder stock, that is, stock from which heavy or so-called cylinder lubricating oil may be produced. This residue or cylinder stock may be washed by suitable aqueous solution of soap as above described and upon reducing its viscosity, by addition of naphtha or other 115 suitable low viscosity oil, it is chilled and the contained solids, of the nature of petro-latum containing amorphous wax, more readily settle out.

120 It will further be understood that any two

or more of the washed distillates from the light wax bearing distillate, the washed distillate resulting from the cracking distillation of heavy wax bearing stock and the 5 washed heavy stock from the heavy wax bearing stock, may be mixed in any suitable proportions and then chilled and pressed to yield slack wax which may then be treated in any of the ways hereinbefore described, 10 or otherwise, for producing paraffine wax or other products.

Referring to Fig. 2, there is indicated one of various forms of cracking distillation of crude petroleum, resulting in various cuts 15 or products any of which, if suitable or desirable, may be washed by my preferred solution of sludge acid soaps or sludge sulfonates.

As indicated, a wax bearing or paraffine 20 distillate is produced; this may be washed with a solution of any of the soaps described, and the washed paraffine distillate may then be chilled and pressed to yield a slack wax which may then be treated by any method, 25 as any of the methods described in connection with Fig. 1, for producing paraffine wax or other products.

The cracking distillation yields also paraffine slops, an oil of higher viscosity than 30 the paraffine distillate and which it has not heretofore been possible immediately to chill and press to procure slack wax.

These paraffine slops may be treated in either of two ways, in general similar or 35 analogous to the modes of treatment of the heavy wax bearing stock in the case of fractional distillation. The paraffine slops may be subjected to a cracking distillation yielding in addition to coke and wax tailings re- 40 run slops which are then washed as hereinbefore described with an aqueous solution of any of the suitable soaps described. The washed re-run slops, generally of sufficiently low viscosity or rendered so by addition of 45 low viscosity oil, may then be chilled and pressed to yield slack wax which may be treated by any suitable method, as any of the methods hereinbefore described, to produce paraffine wax or other products.

50 Or the paraffine slops containing, as aforesaid, the more viscous oil constituents, may be washed by aqueous solution of soap of any suitable character hereinbefore described. The washed paraffine slops may 55 then be suitably diluted with low viscosity oil to reduce viscosity, chilled and pressed to yield slack wax, which may be treated by any suitable method, as any of the modes described, to produce paraffine wax or other 60 products.

It will further be understood that any two or more of the washed paraffine distillates derived from the paraffine distillate, the washed re-run slops derived from cracking paraffine 65 slops, and washed paraffine slops derived

from the paraffine slops may be mixed in any suitable proportions, chilled and pressed to yield slack wax, which may then be treated by any suitable method, as any of the modes hereinbefore described, to produce 70 paraffine wax or other products. Where necessary, of course, the mixture may be reduced in viscosity before chilling and pressing by addition of low viscosity oil; though in general the washed paraffine distillate is 75 of sufficiently low viscosity to allow admixture therewith, without further dilution, of substantial quantities of washed re-run slops or washed paraffine slops.

It will be understood also that the paraffine 80 distillate and paraffine slops may be mixed in any suitable proportions and then washed to produce a mixture of washed paraffine distillate and paraffine slops, which may then be chilled and pressed to produce slack wax 85 which may be treated by any method, as any of the modes herein described, for producing paraffine wax or other products. Or the paraffine distillate and paraffine slops may be separately washed and then mixed in any 90 suitable proportion, chilled and pressed to like ends and purposes above described.

Regarding distillations of the characters of both Figs. 1 and 2, the avoidance of cracking distillation of heavy wax bearing stock 95 and paraffine slops is desirable in that the alternative method of treatment, to wit, the described washing of the heavy wax bearing stock and paraffine slops, ensures that the viscosity, which is reduced if the oil is subjected to cracking distillation, is retained, and this is of importance as to the ultimate yield of higher viscosity oils, as lubricating oils, such as derived from the oils separated from the slack wax in the pressing operation, 100 these oils being indicated in Figs. 1 and 2 as pressed stock and pressed slop oil. By recourse to washing in place of cracking distillation, the yield of high viscosity oils is 105 approximately twice the yield when cracking distillation without washing is employed.

By recourse to the method of treating wax bearing oil as herein described, the viscosity of the oil is at least in some instances increased by the washing before chilling and pressing, and such increase in viscosity is a desirable and valuable improvement in the quality of the oil filtrate.

A further advantage arising from my method of washing a wax bearing oil before 120 chilling and pressing lies in the fact that oils of viscosity somewhat higher than the most viscous oils which could heretofore readily be chilled and pressed may now be chilled and pressed to advantage because of the formation of the larger wax crystals as hereinbefore described. For example, where heretofore a wax bearing oil of viscosity of 67 to 69 seconds Saybolt at 100 degrees F, has generally been the most viscous oil that could 130

readily be chilled and pressed, in accordance with my invention a wax bearing oil of 80 to 82 seconds Saybolt at 100 degrees F. if first washed as described may readily be chilled and pressed.

The quality of all the pressed or filtrate oils herein described, namely, those from which slack wax has been separated, is markedly improved in that they have higher viscosity, require less acid when acid treated, and when acid treated the acid sludges are of higher quality in that they are softer and more readily and completely separated from the sour oils, and the quantities of the sludges formed are less, representing, therefore, less loss by occlusion of oil therein; and less of the oils undergoing acid treatment is lost. Because of the more complete separation of wax from the oils due to my washing treatment, these pressed oils are all of better so-called cold test and are better in all respects, particularly as regards those qualities desirable in a lubricating oil.

As indicated in Fig. 1, the pressed distillate resulting from the light wax bearing distillate is fractionally distilled, yielding lubricating stocks, which are acid treated, by strong or fuming sulphuric acid, yielding sludge and sour oil, the latter neutralized to yield lubricating oil. It will be understood that the pressed distillate and pressed stock referred to in connection with Fig. 1 and the pressed distillate, pressed oil and pressed slop oil referred to in connection with Fig. 2 may undergo similar treatment as to distillation, acid treatment and neutralization to produce lubricating oils.

What I claim is:

1. The method of preparing wax bearing oil for separating wax therefrom, which comprises washing the oil with a soap solution of such concentration as to prevent substantial emulsification thereof and to render the wax more readily separable from the oil.

2. The method of preparing wax bearing oil for separating wax therefrom, which consists in washing the same with an aqueous solution of soap of such concentration and under such conditions that the wax may more readily separate from the oil.

3. The method of preparing wax bearing oil for separating wax therefrom, which consists in washing the same with an aqueous solution of sludge sulfonates of such concentration and under such conditions that the wax may be more readily separated from the oil.

4. The method of preparing wax bearing oil for separating wax therefrom, which consists in washing the same with an aqueous solution of an alkali metal or ammonium salt of organic acids from acid sludge, said solution having such concentration that the wax is rendered more readily separable from the oil.

5. The method of procuring wax from wax bearing oil, which consists in washing the oil with an aqueous solution of soap of such concentration that the wax is rendered more readily separable from the oil, separating the washed oil, and chilling and pressing the same.

6. The method of treating wax bearing oil, which consists in subjecting the same to cracking distillation, and washing a wax bearing distillate with an aqueous solution of soap.

7. The method of treating wax bearing oil, which consists in subjecting the same to cracking distillation, washing a wax bearing distillate with an aqueous solution of soap, and thereafter chilling and pressing the washed distillate.

8. The method of treating wax bearing oils differing materially as to their viscosities, which consists in mixing cuts of different viscosities, washing the same in mixture with each other with an aqueous solution of soap, and chilling and pressing the washed mixture.

9. The method of treating wax bearing oils differing materially as to their viscosities, which consists in mixing cuts of different viscosities, washing said oils with an aqueous solution of soap, mixing the washed oils, and chilling and pressing the mixtures.

10. The method of treating heavy wax bearing oil of the character heretofore requiring treatment by cracking distillation for preparing it for chilling and pressing, which consists in washing the oil with aqueous solution of soap, and chilling and pressing the washed oil.

11. The method of treating heavy wax bearing oil of the character heretofore requiring treatment by cracking distillation for preparing it for chilling and pressing, which consists in washing the oil with aqueous solution of soap, and chilling and pressing the washed oil in the presence of added oil of low viscosity.

12. The method of separating paraffine wax from oil residuum, as cylinder stock, which consists in washing the oil with aqueous solution of soap, and thereafter chilling and settling the same.

13. The method of separating paraffine wax from oil residuum, as cylinder stock, which consists in washing the oil with aqueous solution of soap in the presence of oil of low viscosity, and thereafter chilling and settling the same.

14. The method of treating paraffine wax, which consists in melting the same, and washing the melted mass with an aqueous solution of a salt of organic acid from acid sludge.

15. The method of treating slack wax, which consists in melting the same, and washing the melted mass with an aqueous

solution of a salt of organic acid from acid sludge.

16. The method of treating slack wax, which consists in sweating the same to produce crude scale wax, washing the crude scale wax with a soap solution, and thereafter filtering the washed crude scale wax through a decolorizing agent.

17. The method of treating crude scale paraffine wax, which consists in washing the same with an aqueous solution of soap of such dilution as to prevent substantial emulsification, and thereafter filtering the washed wax through a decolorizing medium.

18. The method of treating wax bearing oil, which consists in washing the oil with an aqueous solution of soap, chilling the washed oil, separating wax therefrom, and acid treating the wax-free oil.

19. The method of producing lubricating oil from wax bearing oil, which consists in washing the wax bearing oil with an aqueous solution of soap, separating wax from the washed oil, deriving lubricating stock from

the wax-free oil, acid treating the lubricating stock, and neutralizing the resultant sour oil to produce lubricating oil.

20. The method of treating wax bearing oil, which consists in washing the oil with an aqueous soap solution, chilling the washed oil, separating crude wax therefrom, and washing said wax with soap solution.

21. The method of treating wax bearing oil, which consists in washing the oil with an aqueous solution of soap, chilling and pressing the washed oil, washing the resulting crude wax with aqueous soap solution, and filtering the washed crude wax.

22. The method of treating mineral oil, as petroleum or petroleum product, which consists in subjecting the same to cracking distillation, and washing a wax bearing distillate with an aqueous solution of soap.

In testimony whereof I have hereunto affixed my signature this 22d day of May, 1919.

CHARLES F. KENNEDY.
